his atty.

UNITED STATES PATENT OFFICE.

HENRY GARDINER LLOYD, OF SURBITON, ENGLAND, ASSIGNOR TO GRANULOID LIMITED, OF LONDON, ENGLAND, A BRITISH COMPANY.

BUILDING OF TENNIS COURTS AND THE LIKE.

Application filed July 1, 1924, Serial No. 723,545, and in Great Britain July 16, 1923.

This invention is for improvements in or relating to the building of tennis courts and the like and has for one of its objects to enable such courts to be built in a systematic manner conducive to satisfactory results in so far as drainage, wearing, and general utility of the courts or the like are concerned.

One feature of the present invention consists in a method of building tennis courts and the like which comprises:—

(a) setting up on the surface to be covered partitions at the marking lines of the court, or if desired at other situations also, so as to divide the said surface into a plurality of separated sections,

(b) filling the said sections with a plastic or semi-solid building material,

(c) removing the said partitions before or after the said fillings have set or dried, and

(d) filling up the spaces left at the situations of the marking lines of the court by the removal of the partitions with building material whereof at least the upper layer is of a colour distinctive from that of the upper surface of the said sections.

The plastic or semi-solid building material employed may take a variety of forms such as concrete, asphalt and the like.

Conveniently, in carrying out the aforesaid step (b), a plurality of charges of the building material are placed into each section and levelled off in turn flush with the upper edges of the surrounding partitions and subsequently compressed so as to form a space below the upper edges of the partitions for the reception of the succeeding charge or charges.

In some circumstances certain of the partitions may be laid in position, at the situation of marking lines of the court, after the lower portion of the charge of building material has been laid in position at such situations. This will provide for the formation of the marking lines at situations where it is unnecessary to provide also for contraction of the building material as it sets or dries.

If desired, in order to promote evenness, the uppermost layer of building material may be levelled off at a higher level than the upper edges of the surrounding partition (for example by a screening board having a recessed operating face) and subsequently compressed by a roller (for example a metal tube) sufficiently long to reach

completely across from the partition at the one side to the partition at the opposite side.

According to another feature of the invention there is provided a collapsible partition whereof the upstanding walls can be closed in towards each other to facilitate the carrying out of the aforesaid step (c). It will be understood that by employing a collapsible partition it will be comparatively easy to remove it without damaging the charges inserted in the sections enclosed by the partition. Conveniently a partition is employed which is composed of strips of angle formation detachably secured together to form a channel whereof at the base one side of one strip rests upon a side of the other strip.

Where a long length of partition is required two or more pairs of the aforesaid strips may be secured together end for end and in such event it is advantageous to arrange that the joint between two strips at the one side of the partition is displaced out of coincidence with the corresponding joint between the strips at the other side of the partition. Thus, the joint can be made without fish plates or the like being required.

For a more complete understanding of the invention there will now be described, by way of example only and with reference to the accompanying drawings, certain methods of, and apparatus for, building tennis courts according to the invention. It is to be understood, however, that the invention is not limited to the precise details set forth.

In these drawings:—

Figure 1 is a partial plan view of a tennis court with its surround.

Figure 2 is a section on the line 2—2 of Figure 1 on a scale larger than that of this latter figure and showing the tennis court in the course of preparation.

Figure 3 is a detail plan view of a portion of a collapsible channel employed in building the tennis court.

Figure 4 is a perspective view showing another appliance that may be used in building the court.

Figure 5 is a similar view of a modified form of appliance, and

Figure 6 is a section, corresponding somewhat to Figure 2, but showing a modified arrangement of the partitions.

Like reference numerals indicate like parts throughout the drawings.

- Referring to Figure 1, a part of the court is shown at 10, the marking lines at 11 and the surround at 12. In Figures 2 and 3 collapsible partitions are shown which, 5 after a suitable foundation has been laid, say of clinker 13, are intended to be set up at the situation of the marking lines 11 of the court and also, if desired, at other situations such as 14, 15, 16 and 17 where no marking 10 lines are required for the court. In this way the surface to be covered will be divided into a plurality of separated sections each of which has subsequently to be filled with a charge.
- 15 The construction of collapsible partition illustrated comprises two angle strips 18 and 19 whereof the upstanding sides constitute the walls of the partition while the base of the strip 19 rests upon the base of the strip 20 18 and is secured thereto by a suitable number of bolts 20. Each bolt 20, in the construction illustrated, passes through a hole 21 in the strip 19 which is elongated laterally of the 25 length of the strip in order to permit the angle strips to be moved towards each other and the partition thus collapsed. If desired, the holes 21 may be extended through to the edge of the strip to form an open-ended slot, as shown in chain lines in Figure 3.
- 30 The partitions may be made of any suitable length that may be required and templates or fitting blocks may be provided for setting the angle strips 18 and 19 the desired distance apart. Where it is necessary to join 35 together lengths of strip in order to make up any desired length of partition, this is preferably done in the manner illustrated in Figure 3. It will be seen that there are shown therein a pair of strips 18 and 19 which are attached endwise to another corresponding pair 180 and 190. The strip 18 reaches under the end of the strip 190 and is secured thereto by bolts 22 whereby the use of fish plates is avoided. The holes through 45 which the bolts 22 have to pass are preferably enlarged in order to permit longitudinal expansion and contraction of the strips to take place in addition to the aforesaid collapsing movement. Adjustment of the strips 50 18 and 19, and 180 and 190 relatively to each other is also thereby permitted.
- The partitions having been set up at the desired situations and held in place say by wooden pegs or other suitable means, the 55 filling of the various sections with the required material can be proceeded with. The upper edges of the partitions may be employed for guiding straight edges for use in levelling off the surface and when the material has set sufficiently the partitions may be collapsed by slackening the bolts connecting the two strips in each partition and moving the strips towards each other. The partitions can then be easily removed and leave 60 65 exposed the various sections which can be

left to dry without being liable to crack. There will be a space all round each section which will facilitate the setting or drying of the material without cracking. Subsequently the spaces left by the removal of 70 the partitions have to be filled in and where these spaces correspond to the marking lines 11 of the court they should be filled in with material whereof at least the upper layer is of a colour distinctive from that of the 75 upper surface of the adjacent sections. In this way permanent marking lines will be provided for the court. The spaces left at such situations as 14, 15, 16 and 17 where no marking lines are required, may be filled 80 in with material having the same colour as the adjacent sections.

It is convenient, particularly when dealing with concrete, to fill each section by a plurality of charges. For instance the first 85 charge of say fairly large stones and cement is shovelled or otherwise placed in position and the top levelled off flush with the upper edges of the partitions. The charge is then pressed by a suitable tool or roller so as to 90 pack its constituent parts fairly close together so that after pressing they occupy say the space indicated at 23 in Figure 2. In this way there will be left between the upper surface of the charge 23 and the upper 95 surface of the partitions, a space into which another charge say of smaller stones or gravel and cement is placed. This may be similarly pressed and occupy, after pressing or rolling, the space indicated at 24 in 100 Figure 2. Between its upper surface and the upper surface of the partitions a space will then be left into which a final or top surface made conveniently of the rounded grains referred to in the earlier patent specification No. 1,484,514 mixed, of course, with cement, may be placed as shown at 25 (Figure 2). The final surface 25 may also be pressed or rolled into position if desired, in which case its upper surface will 105 be somewhat below the level (26) of the upper edges of the partitions, or alternatively it may be screened off slightly above the top of the partitions and rolled down.

By proceeding in the way just described, 115 and suitably graduating the various charges so far as the nature of their constituent parts is concerned, a total filling for each section can be made which will be sufficiently porous to give good drainage, will be sufficiently 120 stable or firm and will have a satisfactory wearing surface.

There is no need to allow each individual charge to set or dry before placing in the succeeding charge or charges, and it will be 125 appreciated that the number of charges employed may be varied as desired. As an example of a suitable proportioning of the parts where three charges only are employed, if the total operative depth of the 130

- partitions is three inches, the nature of the first layer and the pressure applied to it might be such as to leave a free space of three quarters of an inch after the compression has occurred. The second layer when compressed might leave a free space of a quarter of an inch and the third layer when compressed might be one sixteenth of an inch below the upper edges of the partitions.
- 10 The charges for filling the spaces left when the partitions are removed may be of a similar nature to those above described, except in regard to the colouring of the upper layer.
- 15 For compressing the charges in the sections, a tool may be employed of a weight of say twenty to thirty pounds which may either be a roller, or may comprise a rectangular base 27 of metal (see Figure 4) 20 with an upright 28 and cross-handle 29 at the top. The base of the tool is comparatively thin say half an inch and the sides of the rectangle may conveniently be twelve and eight inches. In use the intention is 25 that the operator should rest the base upon a part of the section and should place the balls of his feet upon the upper surface of the base, leaving his heels off the tool. If now he bends somewhat forward so as to 30 throw his weight more upon the balls of his feet a sufficient pressure will be found to be exerted upon the charge to compress it satisfactorily. The tool should then be shifted on to another part of the charge and the 35 operation repeated. It is not the intention that the operator should use the tool to strike blows upon the charge, but the lower charges may be rammed if desired, the lower the layer, the heavier being the permissible blow.
- 40 An alternative form of tool is shown in Figure 5 which is heavier than that shown in Figure 4 and which in operation will not entail the operator transferring so much of his weight to it as will the tool shown in Figure 4. If desired several different weights and forms of pressing tools may be used one after the other in sequence.
- 45 As already mentioned, a roller could be employed instead of a pressing or weighting tool for any or all of the layers. For the lower layers this roller could be of the ordinary "garden roller" type, but for the uppermost layer it may be found convenient 50 to employ a roller in the form say of a metal tube, which is sufficiently long to reach across the full width of the section being rolled and would thus extend over the partitions of each side of such section. In this way the formation of an even surface will be facilitated. Where a long roller is employed 55 as just described, it will be necessary of course, in order that it may operate effectively, that the charge upon which it is to operate should stand above the level of the partitions. The amount which it projects above the partitions must be graduated according to the nature of the material in question, and other circumstances, and it should preferably be so chosen that when 60 the roller has worked down so that its ends rest upon the upper surfaces of the partitions, sufficient rolling of the charge has been accomplished. With some materials, such as a layer made of the rounded grains referred 65 to in the aforesaid earlier patent specification, mixed, of course, with cement, the amount need not be more than one-sixteenth to one eighth of an inch, this figure having been obtained from similar experiments 70 to those from which the other examples given hereinbefore were obtained. In order to prepare the charge for the long roller, a screening board may be employed whereof the middle portion between the parts 75 which rest upon the partitions is at a higher level than the upper surfaces of the partitions.
- 75 In some instances it may be found that the space between the marking lines is so narrow as not to necessitate a partition of the full depth being employed since contraction of the material may safely be allowed to take place in a wider area. For instance the width 30 (Figure 1) may safely be included 80 with the width 31 in so far as allowance for contraction is concerned. In these circumstances, as illustrated in Figure 6, the lower layers may extend obliquely across the width 85 30, 31 and only when the uppermost layer 90 is to be laid need a partition such as 32 be put in place, this being necessary in order to form the marking line. Owing to the partition 32 being comparatively shallow in 95 depth it is not essential that it should be collapsible.
- 100 While the present invention is particularly applicable to the preparation of tennis courts, it is not limited to this particular use. Only half the court may be built at a time whereafter the same set of partitions 105 may be utilized for building the other half. The partitions are preferably made of an overall width corresponding to the width of 110 the marking lines of the court.
- 115 It is to be understood that the invention is not limited to the precise details hereinbefore set forth.
- I claim:—
1. Apparatus for use in the building of tennis courts and the like comprising a collapsible partition and strickle-guide comprising two strips each of angle formation secured 120 together to form a channel whereof the base is constituted by one side of one strip resting upon a side of the other strip.
- 125 2. Apparatus for use in the building of tennis courts and the like comprising a collapsible partition and strickle-guide comprising a plurality of strips each of angle 130

formation secured together in pairs to form channels whereof the base is constituted by one side of one strip of one pair resting upon a side of the other strip of the same pair, which pairs of strips are secured together end to end with the joint at the one side of the partition displaced out of coincidence with the corresponding joint between the strips at the other side of the partition. In testimony whereof I have signed my name to this specification.

HENRY GARDINER LLOYD.
